UNITED STATES PATENT OFFICE.

FREDERICK A. HOWARD, OF READING, PENNSYLVANIA.

CHAIN-BLOCK HOIST.

1,122,503.

Specification of Letters Patent. Patented Dec. 29, 1914.

Application filed February 16, 1914. Serial No. 818,821.

To all whom it may concern:

Be it known that I, FREDERICK A. HOWARD, a citizen of the United States, residing at Reading, in the county of Berks and State of Pennsylvania, have invented certain new and useful Improvements in Chain-Block Hoists, of which the following is a specification.

My invention relates particularly to chain-block hoists, and is directed especially to that type of such devices as are provided with motor-driven mechanism operatively connected with the hand-operated mechanism, to actuate the lifting mechanism.

The principal objects of my invention are, to provide a hand-operated chain-block hoist with power-driven mechanism; to provide means for operatively connecting and disconnecting said power-driven mechanism with the hand-driven mechanism; and to provide means for securely holding said power-driven mechanism in different positions.

Specifically stated, my invention comprehends a hand-operated chain-block hoist having a hand chain wheel provided with gear teeth, motor-driven mechanism having a gear operatively connected with the teeth on said hand chain wheel, and means for shifting said motor-driven mechanism into and out of operative engagement with said hand chain wheel, whereby said hand chain wheel may be manually operated to actuate the lifting mechanism independently of the motor-driven mechanism.

My invention further includes all of the various novel features of construction and arrangement hereinafter more definitely specified.

In the accompanying drawings, Figure 1 is a side elevational view of a chain-block hoist showing a convenient form of my invention; Fig. 2 is a plan sectional view of said hoist taken on the line 2-2 in Fig. 1; Fig. 3 is a transverse vertical sectional view taken on the line 3-3 in Fig. 1; and Fig. 4 is a fragmentary inverted plan view showing a modification of my invention.

In said figures, the side frames 5 and 6 are connected by the bolts 7 and are supported by the hook 8 having trunnions 9 mounted in suitable bearings in the respective frames. The main shaft 10 extends transversely through the side frames 5 and 6 and carries the pinion 11 in mesh with the gears 12 and 13 on the respective shafts 14

and 15, which carry gears 16 and 17 in toothed engagement with the internal gear 18. The gear 18 is mounted on the sleeve 20 which carries the lifting sheave 22 upon which the lifting chain 23 is carried. The main shaft 10 carries the hand chain wheel 25 which is arranged to be manually actuated by the endless chain 26. The mechanism thus far described embodies a well-known construction of chain-block hoist.

As best shown in Fig. 2, the hand chain wheel 25 is provided with beveled gear teeth 28, cut on the inner face thereof, which are arranged to engage with the beveled teeth 29 of the gear 30, which is loosely mounted to rotate on the shaft 31. The gear 30 is provided with internal teeth 32 in toothed engagement with the gears 33 and 34 on the shafts 35 and 36, which carry gears 38 and 39 in toothed engagement with the pinion 42 which is secured on the shaft 31. Said shaft 31 is provided with the gear 44, which is in mesh with the gear 45 on the shaft 46 of the electric motor 50 carried by the side frames 5 and 6.

The differential train of gearing comprising the gears 30, 33, 34, 38, 39, 42 and 44 and their shafts 31, 35 and 36, are mounted in the casing 53, which is provided with the carriage 54 having the grooves 55 in engagement with the guides 57 on the inner faces of the respective frames 5 and 6, as best shown in Fig. 3, and mounted to slide longitudinally thereon, so as to shift the gear 30 into and out of operative engagement with the teeth 28 on the hand chain wheel 25.

In the form of my invention shown in Fig. 1, the frames 5 and 6 are connected by a transverse plate 60 in which is mounted the screw 61 in threaded engagement with the carriage 54. Said screw is provided with a collar 63 arranged to prevent its longitudinal movement, and has the hand wheel 65 mounted thereon, whereby it may be conveniently rotated to effect the longitudinal movement of said carriage. The carriage 54 may be secured in fixed relation to the side frames 5 and 6 in either its operative or inoperative position by the set-screws 67 extending through said frames and in threaded engagement therewith.

The casing 53 inclosing the train of differential gears on the carriage 54 carries the controller mechanism 69 which may be electrically connected in any suitable and

well-known manner with the motor 50. Said controller mechanism is provided with the shaft 70 having the operating lever bar 71, to the free ends of which may be connected the depending controlling chains 72 and 73 for its convenient actuation by the operator.

In the form of my invention shown in Fig. 4, the carriage 54 is provided with a triangular recess 75, the walls of which are arranged to be engaged by the cam 76 on the hand lever 77 which is pivotally mounted on the shaft 78, said carriage being held in either its operative or inoperative position by the set-screws 79.

My invention is especially advantageous in that while the motor-driven mechanism is always in a position to be readily connected with the lifting mechanism, it may be as readily disengaged therefrom by merely shifting it to the inoperative position illustrated in Fig. 4, wherein the teeth of the gearing train are out of engagement with the teeth of the hand chain wheel, so as to permit the free rotation of said hand chain wheel independently of said motor-driven mechanism.

I do not desire to limit my invention to the precise details of construction and arrangement herein set forth, as it is obvious that various modifications may be made therein without departing from the essential features of my invention as defined in the appended claims.

Having thus described my invention, I claim:

1. In a chain-block hoist, the combination with a frame, of a lifting chain sheave, a train of differential gearing connected to 40 rotate said sheave, a hand chain wheel connected with said gearing and having gear teeth thereon, a second train of differential gearing having a gear arranged to mesh with the gear on said hand chain wheel, a 45 motor connected to drive said second gearing train, and means for shifting said second gearing train to operatively engage and disengage its gear with the teeth on said hand chain wheel.

2. In a chain-block hoist, the combination with a frame, of a lifting chain sheave, a train of differential gearing connected to drive said sheave, a hand chain wheel connected with said gearing train and provided with gear teeth, a reciprocating mounting movably carried by said frame, a second train of differential gearing carried by said mounting and having a gear arranged to engage the teeth on said hand chain wheel, 60 a motor carried by said frame, means operatively connecting said motor to drive said second gearing train, means operative to shift said mounting on said frame to op-

eratively engage and disengage the gear of said second gearing train with the teeth on 65 said hand chain wheel, and means arranged to secure said mounting in fixed relation with said frame.

3. In a chain-block hoist, the combination with a frame having guides, of a main driving shaft, a lifting chain sheave carried by said shaft, a train of differential gearing operatively connected with said shaft, a hand chain wheel connected to drive said gearing and having beveled teeth disposed thereon, a carriage slidably mounted in said guides, a second train of differential gearing mounted on said carriage and having a beveled gear arranged to engage the beveled teeth on said hand chain wheel, a motor carried by said frame operatively connected to drive said second gearing train, and means arranged to reciprocate said carriage on said frame to operatively engage and disengage said second gearing train from the teeth of 85 said hand chain wheel.

4. In a chain-block hoist, the combination with a frame, of a lifting chain sheave, a train of differential gearing operatively connected to rotate said sheave, a hand chain wheel operatively connected with said differential gearing and having beveled gear teeth mounted thereon, a carriage slidably mounted on said frame, a second train of differential gearing mounted on said carriage, a screw having a hand wheel mounted to rotate in said frame and having means to prevent it from axial movement, and having threads in engagement with said carriage and arranged to shift it into position to operatively engage and disengage the second gearing train with the teeth of the hand chain wheel, and a motor carried by said frame operatively connected to drive said second gearing train.

5. In a chain-block hoist, the combination with lifting mechanism, of a hand chain wheel operatively connected to actuate said lifting mechanism and having gear teeth mounted thereon, a carriage slidably mounted on said frame, a train of gearing mounted on said carriage and having a gear arranged to engage the teeth on said hand chain wheel, a motor carried by said frame operatively connected with said gearing train, and hand operated means to shift the gearing train into and out of operative engagement with the teeth on said hand chain wheel.

In witness whereof, I have hereunto set 120 my hand this 14th day of February, A. D., 1914.

FREDERICK A. HOWARD.
